UNITED STATES PATENT OFFICE.

JOSEPH PHILANDER HASTY, OF SAN DIEGO, CALIFORNIA.

SWITCH STAND.

Application filed April 27, 1925. Serial No. 26,200.

To all whom it may concern:

Be it known that I, JOSEPH PHILANDER HASTY, a citizen of the United States, residing at San Diego, in the county of San Diego and State of California, have invented a new and useful Switch Stand, of which the following is a specification.

This invention aims to provide a novel switch throwing mechanism whereby a signal will be given when a train runs through a switch without having the switch points set properly. The invention aims, further, to provide novel means for operating the switch points. A further object of the invention is to provide a device of the class described which will withstand severe use, and be so constructed that its operation will not be interfered with appreciably by snow or ice.

It is within the province of the disclosure to improve generally and to enhance the utility of devices of that sort to which the invention appertains.

With the above and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed without departing from the spirit of the invention.

In the accompanying drawings:—

Figure 1 shows in top plan, a device constructed in accordance with the invention;

Figure 2 is a side elevation;

Figure 3 is a vertical section wherein parts appear in elevation;

Figure 4 is a bottom plan of the switch stand;

Figure 5 is a section taken about on the line 5—5 of Figure 4; and

Figure 6 is a sectional view showing the bracket on the switch stand.

The numeral 1 marks the main line rails of a railroad track, the siding rails appearing at 2, the switch points at 3 and the switch ties at 4. The switch points 3 are operatively connected in the common way by a bridle 5 which is pivoted at 6 to a link 7.

The numeral 8 marks a switch stand including a base 9 and a pedestal 10 upstanding from the base, the base being secured at 11 to the switch ties 4. In the base 9 of the switch stand 8 and in the pedestal thereof, a

vertical shaft 12 is journaled, the shaft being equipped at its lower end with a crank arm 14, including an upstanding portion. The base 9 of the switch stand 8 is provided with a raised lower surface 15, there being recesses 16 extended inwardly from opposite edges of the base 9 and interrupting the said surface 15, as indicated in Figure 4 of the drawings. The inner end of the link 7 is mounted on the upstanding portion of the crank arm 14 of the shaft 12. The upstanding portion of the crank arm 14 terminates so close to the lower surface 15 of the base 9 of the switch stand that, when the crank arm 14 is so disposed that the switch points 3 are set either for the main line or for the siding, the inner end of the link 7 cannot escape upwardly off the crank arm. When, however, the crank arm 14 is so disposed that the upstanding portion thereof is beneath one of the recesses 16, the inner end of the link 7 may be mounted readily on the upstanding portion of the crank arm 14. The device, therefore, is so constructed that it affords means whereby the link 7 may be assembled readily with the crank arm 14, and whereby, when the device is in use, the link will remain securely assembled with the crank arm.

The numeral 17 marks a disk-like keeper having any desired number of notches or seats 18 in its edge, there being a stop pin 19 in the upper surface of the keeper, adjacent to each notch. The shaft 12 extends through the keeper 17. The keeper 17 has a downwardly and outwardly extended angular arm 20 movable in a bracket 21 secured to the pedestal 10 of the switch stand 8. A keeper 17 and its arm 20 ordinarily are fixed with respect to the switch stand 8, because the bracket 21 carries a shear member 27, engaging the arm 20, the shear member being weak enough so that it can be broken under extraordinary conditions which will be alluded to hereinafter. On the outer end of the arm 20 there is a standard 22 carrying a day signal 23, the standard terminating at its upper end in bifurcations 24 carrying translucent colored screens 25 disposed on opposite sides of a lamp 26 mounted on the upper end of the shaft 12.

The numeral 28 designates a casing or support which is secured at 29 to the shaft 12, the casing or support being disposed immediately above the keeper 17. In its under

surface, the casing 28 has a groove 42, wherein the stop pin 19 is received when the casing 28 is rotated with respect to the keeper 17. The numeral 30 designates a latch, in the form of a lever, pivoted or fulcrumed at 31 on the casing 28, the latch having an arm 32 wherein there is an opening 33 adapted to receive a lock 34 secured by a chain 35 or otherwise to any accessible portion of the casing 28.

When the latch lever 30 is swung downwardly into the notch or seat 18 of the keeper 17, and when the lock 34 is mounted in the opening 33 of the latch lever, the latch lever cannot be swung upwardly out of the notch 18, and the switch mechanism is locked in any position to which it may have been set. When the lever 30 is swung upwardly out of the notch 18 in the keeper 17, then the casing 28 and the shaft 12 may be rotated, the crank arm 14 on the lower end of the shaft 12 operating through the link 7 and the bridle 5 to move the switch points 3.

25 The screens 25 normally stand parallel to the track, so that they will not obscure the lamp 26 with respect to a train which is moving along the track. If a train enters the switch when the switch is closed, and 30 forces or splits the switch, then the shaft 12 will be rotated forcibly, through the instrumentality of the bridle 5, the link 6 and the crank arm 14 on the shaft 12. The keeper 17 will rotate with the casing 28 and the shaft 12, because the casing 28 is coupled to the keeper 17 by means of the latch 30. When the keeper 17 is forcibly rotated, as aforesaid, the shear member 27 will break, and no damage will be done to the mechanism. When the keeper 17 is rotated, the 35 arm 20 and the standard 22 will be swung, thereby disposing the screens 25 crosswise with respect to the track, the screens so altering the color of the light proceeding 40 from the lamp 26 that a person on an approaching train will be admonished at once as to what has taken place with respect to the switch points.

50 The device forming the subject matter of this application is safe, simple and durable, positive in action and always ready for use. It is so constructed as to obviate many of the delays which are encountered in the moving of trains. The general construction of the device is such that the point of connection between the crank arm 14 and the link 7 is well protected from sleet and snow. It is to be observed that the pedestal 55 10 does not rise from the base plate 9 at the geometrical center of the base plate. Conse-

quently, when the switch stand is mounted in place, as shown in Figure 1, there will be ample room between the switch ties 4 for the bridle 5 and the link 7 to work.

Having thus described the invention, 65 what is claimed is:

1. In a device of the class described, a stand, a keeper, a frangible connection between the stand and the keeper, a shaft journaled in the stand, means for connecting the shaft with a switch point, a latch engaging the keeper, means for mounting the latch on the shaft, a signal on the shaft, a screen, and means for mounting the screen for movement with the keeper, thereby to 70 shift the screen with respect to the signal when the frangible connection is broken and when the keeper moves with the shaft.

2. In a device of the class described, a stand, a keeper on the stand, a shaft journaled in the stand, a support secured to the shaft, a latch pivoted to the support and engaging the keeper, a bracket on the stand, a frangible connection between the keeper and the bracket, a signal on the shaft, a 80 screen, and means for connecting the screen to the keeper, for movement with the keeper and the shaft with respect to the signal.

3. In a device of the class described, a stand, a shaft rotatable in the stand, a keeper through which the shaft passes, a support on the shaft, a latch movably carried by the support and cooperating with the keeper, a bracket on the stand, the keeper being provided with an angular arm 85 extended downwardly and outwardly through the bracket, a standard on the arm, a signal on the shaft, and a screen carried by the arm and movable with respect to the signal, and a frangible connection between 90 the arm and the bracket.

4. In a device of the class described, a standard comprising a base, a shaft journaled in the standard and supplied at its lower end with a crank including an upstanding portion, a link on the upstanding portion of the crank, the upstanding portion of the crank being disposed so close to the lower surface of the base that the link 100 cannot be detached accidentally from said 110 portion of the crank, the base being provided in its edge with a recess, and the link being detachable from the upstanding portion of the crank when the upstanding portion of the crank is immediately below the 115 recess.

In testimony that I claim the foregoing as my own, I have hereto affixed my signature.

JOSEPH PHILANDER HASTY.
